(57) **CLAIM**

The ornamental design for a snowmobile ski, as shown and described.

DESCRIPTION

FIG. 1 is a perspective illustration, from the front and right side, of the snowmobile ski according to my design;

FIG. 2 is a rear elevational view thereof;

FIG. 3 is a front elevational view thereof;

FIG. 4 is a top plan view thereof;

FIG. 5 is a bottom plan view thereof;

FIG. 6 is a right side elevational view thereof; and,

FIG. 7 is a left side elevational view thereof.

In each of FIGS. 1–7, the broken lines showing structure are for illustrative purposes only and form no part of the claimed design.
